STEP-UP SWITCH

Theodore Obszarny, Chicago, Ill., assignor to
 Guardian Electric Mfg. Co., Chicago, Ill., a corporation of Illinois

Application December 22, 1938, Serial No. 247,207

8 Claims. (Cl. 74—150)

The present invention relates to step-up switches of the type for selectively completing portions of one or more of a plurality of different electrical circuits. Switches of this class are used in conjunction with a relatively large number of different types of apparatus, such as in signs, signal systems, control systems, communication systems, games and other types of equipment.

One of the objects of this invention is to provide a novel, simple, compact step-up switch which is efficient and positive in operation, and relatively inexpensive to manufacture.

Another object is to provide an improved switch of the character indicated, having spring means for returning the contact arm to starting position, under control of mechanical timing means, which permits step-by-step advancement of the contact arm only as long as the means for moving the arm is actuated successively within predetermined periodic intervals of time.

A further object is to provide an improved switch of the character indicated, having a plurality of series of contacts and separate contact arms for each series, arranged for step-by-step registration with the respective series of contacts, and driving means including separately actuated elements for moving said arms sequentially and independently of each other.

Still another object of the invention is to provide an improved switch of the character indicated, having two series of contacts and separate contact arms therefor, arranged for step-by-step registration with said contacts, separately actuated elements for moving said arms sequentially and independently of each other, together with driving means for moving said elements in step-by-step fashion, said elements being formed for causing said driving means to first operate upon one for a predetermined number of actuations and then upon the other of said elements.

Other objects and advantages of the present invention will appear from the following description, taken in connection with the accompanying drawings, in which—

Fig. 1 is a plan view of the step-up switch embodying the present invention.

Fig. 2 is a plan view of the switch looking from the opposite side with respect to Fig. 1.

Fig. 3 is a side elevation of the switch.

Fig. 4 is a view similar to Fig. 1, on an enlarged scale, with parts broken away and omitted, showing the mechanism in a position of adjustment in which the primary contact arm has been moved to its final position of adjustment and the driving pawl is shown in position ready to commence actuation upon the secondary ratchet wheel for moving the secondary contact arm in step-by-step fashion.

Fig. 5 is a fragmentary view similar to Fig. 4, with portions broken away to show details of

construction, with the parts in position of adjustment showing the driving pawl operating upon the secondary ratchet wheel in the process of adjusting the secondary contact arm in step-by-step fashion.

Fig. 6 is an enlarged view similar to Fig. 4, with certain parts omitted for clarity, showing the parts in position of adjustment at which the driving pawl is engaging the secondary check pawl to release the secondary ratchet wheel for returning same, together with the secondary contact arm, to starting position.

Fig. 7 is a top view of the switch mechanism.

Fig. 8 is a vertical section through the switch, taken as indicated at line 8—8 on Fig. 4.

Fig. 9 is a perspective view of the primary and secondary ratchet wheels.

Fig. 10 is a sectional view through the mechanical timing mechanism, taken as indicated at line 10—10 on Fig. 4.

As illustrative of one specific application or use of the step-up switch embodying the present invention, attention is directed to the disclosure on pages 11, 12 and 43 of October 1938 issue of 25 "Service Radio," published by Bryan Davis Publishing Company, New York city, New York, wherein an equivalent type of stepper unit is employed for remotely controlling the operation of a radio receiving apparatus.

30 Referring now in detail to the drawings, the switch constituting the present invention may be understood to be a unitary structure, arranged for convenient mounting in association with various types of apparatus. The switch includes 35 a mounting panel 10 of sheet metal, in which is journaled at right angles thereto a shaft or arbor 11. Supported on the rear side of the panel, as may be seen in Figs. 1, 4 and 5, is a primary set 40 of contacts, indicated at 12, 12^a, 12^b, 12^c and 12^d, which are carried on a panel of insulating material, indicated at 13, rigidly attached to said mounting member by screws 14. Cooperating with said set of primary contacts is a rotatable contact arm 15, for convenience hereinafter 45 designated as the primary contact arm, which is staked to a bushing 16 loosely journaled on the shaft 11. Staked on the opposite end of said bushing is a primary ratchet wheel 18, and by virtue of which connection said ratchet wheel, bushing and primary contact arm are rotatable as a unit, in step-by-step fashion.

50 Mounted on the outer face of the mounting panel 10, by means of studs 19, is a disk 20 of insulating material, on which is mounted a secondary series of contacts, indicated at 21, 21^a, 21^b, 21^c, 21^d, 21^e, 21^f and 21^g. It is to be understood that the outer ends of said contacts of both the primary and secondary groups are connected in a suitable manner, such as by soldering, to conductor wires, for completing portions of various electrical circuits to be controlled by

the step-up switch. A secondary, rotatable contact arm 23 is staked to a bushing 24, which is rigidly attached by set screw 24^a to the outer end of the shaft 11 for rotation therewith. The secondary contact arm 23 is controlled by, and movable as a unit with, a secondary ratchet wheel 26, in step-by-step fashion; said ratchet wheel is rigidly staked to a bushing 27 which, in turn, is attached by set screw 27^a to the shaft 11. A spacer washer 28 is mounted loosely on said shaft, between the primary and secondary ratchet wheels 18 and 26, as seen in Fig. 8. The ratchet wheels, together with the bushings and contact arms, are maintained in assembled relation with respect to the mounting panel 10 by means of clamp plate 30, the ends of which are rigidly secured by means of studs 31 to said mounting plate 10, in spaced-apart relation, as seen in the drawings.

The primary and secondary ratchet wheels 18 and 26 are herein designated as such merely for convenience, but, as may be seen in Fig. 9 of the drawings, these elements are in the form of segments and have only a portion of their periphery formed with teeth. More particularly, in the primary ratchet wheel 18 there are three main teeth, as indicated at 18^a, and one special tooth, as indicated at 18^b. Therefore, when the driving pawl, which will hereinafter be described, engages with said teeth 18^a sequentially, the ratchet wheel is moved, step-by-step, simultaneously moving the primary contact arm 15 over the corresponding contacts 12^a, 12^b and 12^c, and when the driving pawl engages the special tooth 18^b the primary contact arm is moved into engagement or registration with the last of the contacts of the primary series, as indicated at 12^d. The lower portion of the primary ratchet wheel is formed with a notch, as indicated at 18^c, to form a hook for the closed loop of a tension spring 32, the other end of which spring is secured to a stud 33, carried on a bracket 33^a which, in turn, is secured to the mounting plate 10. The spring 32, when the ratchet wheel 18 is free, returns said ratchet wheel, together with the primary contact arm 15, to the starting position, such as indicated in Fig. 1. To arrest the ratchet wheel and primary contact arm in proper position, the ratchet wheel is formed with an abutment shoulder 18^d, which engages a stop member 34 carried by the bracket member 33^a.

It will be observed that the secondary ratchet wheel is formed with a multiplicity of teeth, indicated at 26^a, which, desirably, should correspond in number to at least the number of contacts comprising the secondary series of contact members. Said secondary ratchet wheel is also provided at its lower portion with an abutment shoulder 26^b adapted to engage the stop 34 to arrest the ratchet wheel, together with the secondary contact arm 23, in an initial or starting position, as indicated in Figs. 2 and 4. It may be understood that said stop is formed of fibrous or like material, to reduce noise. The secondary ratchet wheel 26 is, when free, caused to be returned, together with the secondary contact arm, to a starting position by means of a coil spring 36, circumscribing the end of the shaft 11, projecting rearwardly beyond the clamp plate 30, and having one end extending into a slot 11^a formed in the end of the shaft, the other end of said spring being fixedly secured to the clamp plate 30. It will now be apparent that as the shaft 11 is rotated, incident to the step-by-step movement of the secondary ratchet wheel, said

spring becomes tensioned, so that upon disengagement of the secondary ratchet wheel, by the holding means hereinafter to be described, said shaft, together with the secondary ratchet wheel 26, and secondary contact arm 23, is caused to return to starting position. It will be noted from the drawings, particularly Fig. 4, that the radius defining the teeth of the secondary ratchet wheel is substantially less than the radius of the root of the teeth 18^a of the primary ratchet wheel. The purpose of this constructional difference will be apparent in connection with the description of the action of the driving pawl, to be hereinafter described.

The driving means for moving the primary and secondary ratchet wheels in step-by-step fashion includes an electro-magnet 40 mounted in a bracket 41 which, in turn, is secured to the mounting plate 10. Said electro-magnet includes a core 42, with which cooperates an oscillatable armature 43, pivotally mounted at its lower end in the bracket 41 and yieldingly urged to its outermost position, as seen in Fig. 4, by means of a spring 44 having one end connected to the lower end of the armature, and the opposite end to a lug 41^a of said bracket 41. The upper end of the armature is provided with a bracket 46 in the form of a hook, engaging a flange of the end of the electro-magnet for limiting the outward movement of the armature with respect to the core 42. Rigidly connected to, and extending upwardly from, said armature is a carrier bracket 48, which is formed with a pair of spaced-apart ears 48^a, in the upper ends of which are journaled the ends of a U-shaped bale or driving pawl 50 which, for convenience, is formed of a piece of relatively rigid wire. Said driving pawl is yieldingly urged downwardly with the closed end thereof in position for engaging the teeth of either the primary or secondary ratchet wheels by means of a coil spring 51 having one end connected to and seated in a notch 50^a formed in one of the legs of the bale-like driving pawl, the opposite end of said spring being connected to the carrier bracket 48. It will now be apparent that as the electro-magnet is energized the attraction of the armature 43 to the core 42 moves the closed end of the bale-like driving pawl into engagement with the teeth of the ratchet wheels. To insure maintaining the driving pawl in position for properly engaging said teeth of the ratchet wheels I provide a stop plate 52 rigidly attached by a stud 53 to the mounting plate, in a plane intermediate the two ratchet wheels, as may be seen in Fig. 3. The outer end of said member 52 is formed as a finger-grip to permit convenient adjustment of said member 52 in the initial assembly of the switch unit.

It will now be apparent that said driving pawl 50, upon being successively reciprocated by energization of the electro-magnet, advances the primary ratchet wheel 18, together with the primary contact arm 15, in step-by-step fashion, by engagement with the ratchet wheel teeth 18^a and the special tooth 18^b and, after movement of the ratchet wheel 18 by the driving pawl engaging the special tooth 18^b, said ratchet wheel is positioned, as seen in Fig. 4, so that in the next actuation of the driving pawl the closed end thereof rides beneath said special tooth and engages the teeth 26^a of the secondary ratchet pawl 26, for advancing same, together with the secondary contact arm 23, in step-by-step adjustment. It is to be understood, of course, that during the reciprocating action of the driving

pawl 50, said ratchet wheels 18 and 26 are held in advanced position by detent means to be hereinafter described; or said ratchet wheels, together with their corresponding contact arms, would return to starting position after each actuation.

Co-axially mounted on a stud 55 secured to the rear side of the mounting plate 10 are trans-axially spaced apart, primary and secondary check pawls 56 and 57, each having laterally ex-
tending lugs 56^a and 57^a, respectively, for engage-
ment in the teeth of the corresponding primary
and secondary ratchet wheels 18 and 26, as may
be seen in Fig. 8. The primary check pawl is of
bell crank type, including a rearwardly extending
lever arm 56^b, the end of which is formed with a
hook 56^c for engaging the loop end of a coil spring
58, the opposite end of which spring is secured
by a pin 58^a to the mounting plate. It will be
apparent that normally the spring 58 tends to
urge the lug 56^a of the check pawl 56 into engage-
ment with the teeth of the primary ratchet wheel.
The extreme end portion of the arm 56^b is formed
with a laterally extending lug 56^d, with which en-
gages the end of a spring-pressed sector rack 59
of a mechanical timing mechanism, to be hereinafter described. At this time it may suffice to
say that said segment is normally spring-pressed
downwardly on said lug 56^d to overcome the
action of the coil spring 58, and normally main-
tains the lug 56^a of the check pawl out of en-
gagement with the teeth of the ratchet wheel.
The secondary check pawl 57 is formed at its
rear lower portion with a hook 57^b for engage-
ment by the closed end of a spring 60, the oppo-
site end of which is connected to said lug 56^d of
the lever arm 56^b of said primary check pawl.
By virtue of such arrangement the spring 60
normally maintains the check pawl 57 in engage-
ment with the teeth of the secondary ratchet
wheel 26 for maintaining same, together with its
secondary contact arm 23, in the last position
of step-by-step adjustment. The forward end
or nose of the secondary check pawl 57 is formed
as a cam 57^c disposed in the path of travel of
the closed end of the hale-like driving pawl 50
during the movement of said pawl into engage-
ment with the special tooth 18^b of the primary
ratchet wheel 18 which, it will be apparent, and
as seen in Fig. 6, raises the driving pawl slightly
above its normal path of movement so that it
engages cam-wise with said cam end 57^c of the
check pawl, lifting the lug 57^a out of engagement
with the teeth 26^a of the secondary ratchet wheel,
thereby permitting said secondary ratchet wheel,
together with the secondary contact arm 23, to be
returned to starting position under influence of
spring 36. It will be noted that this action takes
place when the primary contact arm 15 and pri-
mary ratchet wheel 18 arrive at their final posi-
tion of adjustment, at which said arm engages
the last contact member, indicated at 12^d, of the
primary series.

It will now be clear, as above stated, that dur-
ing the first four continuous reciprocations of
the driving pawl 50, said pawl first engages the
three teeth 18^a and then the special tooth 18^b
of the primary ratchet wheel 18, advancing said
ratchet wheel step-by-step for disposing the pri-
mary contact arm 15 in registration with contact
12^d of the primary contact series; and during
the last actuation of the driving pawl in engag-
ing the special tooth 18^b of the primary ratchet
wheel, said driving pawl acts cam-wise against
the end of the secondary check pawl 57, lifting

same out of engagement with the teeth of the
secondary ratchet wheel 26, permitting same, to-
gether with the secondary contact arm 23, to be
returned to starting position. In the next suc-
cessive actuation of the driving pawl 50, said
pawl passes beneath the special tooth 18^b of the
primary ratchet wheel, and engages in the first
tooth 26^a of the secondary ratchet wheel, thereby
advancing said ratchet wheel 26 simultaneously
with the secondary contact arm 23. And any
number of successive actuations thereafter of the
driving pawl causes step-by-step advancement of
the secondary ratchet wheel with the secondary
contact arm to a desired position of adjustment
for completing a portion of some predetermined
electrical circuit through a corresponding contact
with which the secondary contact arm is per-
mitted to register. There may be occasions when
it is desired to complete merely a portion of some
predetermined electrical circuit, including one of
the respective contacts 12^a, 12^b, 12^c or 12^d, of the
primary set of contacts, in which case the driving
pawl is actuated a corresponding number of times
to position the primary contact arm 15 in regis-
tration with the proper contact of said series.
It is to be understood that the positioning of the
respective contact arms in engagement with a
predetermined contact of either of the respective
series of contacts is determined by the number
of successive actuations of the driving pawl caused
by magnetization of the electro-magnet 40 and any
convenient, well-known means may be em-
ployed for imparting electrical current impulses
to the electro-magnet in a predetermined num-
ber of uniformly timed intervals. For proper
control of the primary check pawl 56 by the
timer mechanism hereinafter to be described, it
has been found that the rate of impulses of
electric current imparted to the electro-magnet
for satisfactory and proper functioning of the
mechanism, should be between five and ten pulsations
per second. It will be manifest that the rate of pulsations will also be the rate of actuation
of the contact arm in moving from contact
to contact. Therefore, it is apparent that such
a relatively short period of time of completion
of the electrical circuit by the contact arm mov-
ing from contact to contact is insufficient, gen-
erally speaking, to cause operation of the mech-
anism actuated by the electrical circuit thus com-
pleted. The reason for this relatively rapid rate
of pulsations will be apparent from the descrip-
tion of the timing action employed for control-
ling the primary check pawl.

The timing mechanism herein disclosed is of a
mechanical nature, and includes a frame mem-
ber 61 mounted on studs 62 for supporting same
in spaced relation to the mounting plate 10. Supported
from this frame member by means of
studs 63 is an auxiliary frame or support 64, be-
tween which frame members is journaled a shaft
65 on which is loosely mounted a pinion 66,
meshed with the sector rack 59. Surrounding
said shaft 65 is a coil spring 67 having one end
secured in said pinion, as seen in Fig. 10, and the
opposite end of which frictionally engages the
hub of an escapement gear 68 journaled on the
opposite end of the shaft 65. Journaled in said
frame members 61, 64 is another shaft 69, on
which is rigidly mounted a disk 70 carrying a pair
of diametrically, oppositely disposed, laterally ex-
tending pins 71 positioned in close proximity to
the toothed periphery of the gear 68. It will be
understood that the escapement gear 68, to-
gether with the pins 71, acts somewhat as a brake

to maintain a uniform speed of rotation of the pinion 66 when actuated by the segment rack 59. By virtue of the construction described, the spring 67 constitutes a one way friction drive for the escapement gear 68, which is prevented from rotating in counterclockwise direction (as seen in Figure 4) by the pins 71 of the oscillatable disk 70, during rotation of pinion 66 incident to the upward rocking movement of the segment gear 59. As the escapement gear 68 rotates, the disk 70 oscillates, first projecting one of the pins 70 into engagement with the teeth of the escapement wheel 68 and which pin is then cammed out of engagement due to the shape of the teeth of said wheel, causing the opposite pin to be projected into engagement with the toothed periphery of said wheel, and vice versa. As will presently be described, when the armature 43 is attracted to the core 42 of the electro-magnet, the segmental rack 59 is rocked upwardly about the pivot 72 in the end of the frame 61, thereby rotating the pinion 66, and due to the action of pins 71 of disk 70, the spring 67 cannot frictionally rotate the escapement wheel 68. Upon the return movement of the segment rack 59 the spring 67 is permitted to frictionally drive the escapement wheel 68, which is controlled by the action of pins 71 of the oscillatable disk 70, and thereby causes said wheel 68 to rotate at a uniform rate of speed. Such rotation of the wheel 68 tends to maintain a uniform speed of return movement of the segment rack, and which thereby provides a definite timing action for the period of time that said primary check pawl 56 is permitted to function to retain the primary ratchet wheel 18 in the last position of adjustment attained by actuation of the driving pawl 50.

Said segment rack, as shown, is a two-piece construction, including a supporting body 74, to which the rack proper is pivoted at 75. Said body portion 74 includes a leg portion projecting downwardly from the main pivot 72 in position to be engaged by the carrier bracket 48 when the armature 43 is attracted to the core 42 of the electro-magnet, which action rocks the segment rack 59 in an upward direction, and which, as above described, disengages the end of the rack with the lug 56^d of the primary check pawl, permitting the primary check pawl 56 to retain the primary ratchet wheel 18, together with the primary contact arm 15, in the last position of adjustment effected by actuation of the driving pawl 50. The segment rack 59 is held in proper position to the pinion 66 by a coil spring 78 connected to lugs 59^a and 74^a of the respective parts of the rack unit. The rack unit, including the operating arm 76, is yieldingly urged to the position seen in Fig. 4 by means of a coil spring 80, connecting a lug 74^b of said body portion of the segment rack unit, and a lug 61^a of the frame member 61 of the timer mechanism.

The step-up switch constituting the present invention is positive in operation and is relatively simple in construction as compared to equivalent step-up switches for performing similar functions; in fact, the number of parts utilized are substantially less, and the cost of manufacture is greatly reduced as compared with the equivalent type units that are now commercially available.

Although I have herein shown and described a preferred embodiment of my invention, manifestly it is capable of considerable modification and re-arrangement of parts without departing from the spirit and scope thereof. I do not,

therefore, wish to be understood as limiting this invention to the precise embodiment herein disclosed, except as I may be so limited in the appended claims.

5 I claim:

1. In a step-by-step positioning device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, and means associated with and movable by the primary ratchet wheel into the path of travel of the driving pawl after said predetermined number of actuations to preclude further movement of the primary ratchet wheel by said pawl, whereby further actuation of said driving pawl rotates the secondary ratchet wheel in step-by-step adjustment.

2. In a step-by-step positioning device, a shaft, a primary ratchet wheel and a secondary ratchet wheel, said ratchet wheels being mounted on said shaft for rotation independently of each other, a reciprocating pawl for driving said ratchet wheels and adapted upon one or more of a predetermined number of actuations for rotating the primary ratchet wheel in step-by-step adjustment, means associated with and movable by the primary ratchet wheel into the path of travel of the driving pawl after said predetermined number of actuations, to preclude further movement of the primary ratchet wheel by said pawl, whereby further actuation of said driving pawl rotates the secondary ratchet wheel in step-by-step adjustment, one of said ratchet wheels being fixed on the shaft and the other free on said shaft, spring means tending to rotate said shaft in opposition to operating direction of rotation of said fixed ratchet wheel, and spring means opposing movement of the loose ratchet wheel in operating direction.

3. In a step-by-step positioning device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, means associated with and movable by the primary ratchet wheel into the path of travel of the driving pawl after said predetermined number of actuations to preclude further movement of the primary ratchet wheel by said pawl, whereby further actuation of said driving pawl rotates the secondary ratchet wheel in step-by-step adjustment, separate spring-pressed check pawls for the respective ratchet wheels, said last mentioned means comprising the last operating tooth of the primary ratchet wheel, formed as a cam for raising said driving pawl during its actuating stroke, and spring means for resetting said ratchet wheels to starting position, upon disengagement of said check pawls.

4. In a step-by-step positioning device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, and means comprising the last operating tooth of the

primary ratchet wheel formed as a cam for raising said driving pawl after said predetermined number of actuations to preclude further movement of the primary ratchet wheel by said pawl, whereby further actuation of said driving pawl rotates the secondary ratchet wheel in step-by-step adjustment, the teeth of the primary ratchet wheel, comprising the angular range of movement of said wheel, being formed about a radius greater than the radius of the teeth of the secondary ratchet wheel, and the peripheral portion of said primary ratchet wheel, beyond the last tooth thereof, and within the range of angular movement of the secondary ratchet wheel, being less than the radius of the teeth of said secondary ratchet wheel.

5. In a step-by-step positioning device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, means associated with and movable by the primary ratchet wheel into the path of travel of the driving pawl after said predetermined number of actuations to preclude further movement of the primary ratchet wheel by said pawl, whereby further actuation of said driving pawl rotates the secondary ratchet wheel in step-by-step adjustment, separate spring-pressed check pawls for the respective ratchet wheels, said last mentioned means comprising the last operating tooth of the primary ratchet wheel, formed as a cam for raising said driving pawl during its actuating stroke, and spring means for resetting said ratchet wheels to starting position, upon disengagement of said check pawls, the end of the secondary check pawl being formed as a cam and disposed adjacent the path of travel of the driving pawl, for engagement by said driving pawl when the latter engages the cam tooth of the primary ratchet wheel for disengaging said secondary check pawl to permit return of the secondary ratchet wheel to starting position, preparatory to step-by-step adjustment thereof, upon continued actuation of the driving pawl.

6. In a step-by-step device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, means comprising the last operating tooth of the primary ratchet wheel formed as a cam for raising said driving pawl after said predetermined number of actuations to preclude further movement of the primary ratchet wheel by said pawl, whereby further actuation of said driving pawl rotates the secondary ratchet wheel in step-by-step adjustment, the teeth of the primary ratchet wheel comprising the angular range of movement of said wheel being formed about a radius greater than the radius of the teeth of the secondary ratchet wheel, and the peripheral portion of said primary ratchet wheel, beyond the last tooth thereof, and within the range of angular movement of the secondary ratchet wheel, being less than the radius of the teeth of said secondary ratchet wheel, separate spring-pressed check pawls for the respective ratchet wheels, and spring means for resetting said ratchet wheels to starting po-

5 sition, upon disengagement of said check pawls, the end of the secondary check pawl being formed as a cam and disposed adjacent the path of travel of the driving pawl for engagement by said driving pawl when the latter engages the cam tooth of the primary ratchet wheel for disengaging said secondary check pawl to permit return of the secondary ratchet wheel to starting position, preparatory to step-by-step adjustment thereof, upon continued actuation of the driving pawl.

7. In a step-by-step positioning device, a primary ratchet wheel and a secondary ratchet wheel, said ratchet wheels being mounted for rotation independently of each other, a reciprocating pawl for driving said ratchet wheels and adapted upon one or more of a predetermined number of actuations for rotating the primary ratchet wheel in step-by-step adjustment, means associated with and movable by the primary ratchet wheel into the path of travel of the driving pawl after said predetermined number of actuations to preclude further movement of the primary ratchet wheel by said pawl, whereby further actuation of said driving pawl rotates the secondary ratchet wheel in step-by-step adjustment, separate spring-pressed check pawls for the respective ratchet wheels, said last mentioned means comprising the last operating tooth of the primary ratchet wheel, formed as a cam for raising said driving pawl during its actuating stroke, spring means for resetting said ratchet wheels to starting position, upon disengagement of said check pawls, the end of the secondary check pawl being formed as a cam and disposed adjacent the path of travel of the driving pawl for engagement by said driving pawl when the latter engages the cam tooth of the primary ratchet wheel for disengaging said secondary check pawl to permit return of the secondary ratchet wheel to starting position, preparatory to step-by-step adjustment thereof, upon continued actuation of the driving pawl including an electro-magnet, adapted to be energized at periodic intervals of time, and having an oscillatable armature pivotally connected to said driving pawl, and spring means acting on said driving pawl to permit pivotal movement thereof upon encounter with said cam tooth of the primary ratchet wheel.

8. In a step-by-step positioning device, a ratchet wheel, a reciprocating pawl for driving said ratchet wheel and adapted upon one or more of a predetermined number of actuations for rotating said wheel in step-by-step adjustment, 55 electro-magnetic means adapted to be energized at periodic intervals of time and having an armature operably connected to said driving pawl, a spring-pressed check pawl for said ratchet wheel, spring means for resetting said ratchet wheel to starting position upon disengagement of the check pawl, and gear and pinion type timing mechanism for controlling said check pawl for precluding resetting of said ratchet wheel to starting position during the time that said driving pawl is being successively actuated by said electro-magnetic means within periodic intervals of time, said timing mechanism including a segment gear having an operating arm positioned for engagement by the armature of the electro-magnetic means for energizing said mechanism, and an abutment shoulder adapted to engage an arm of the check pawl for holding it out of engagement with said ratchet wheel while said mechanism is deenergized.
